UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER-CRINKLING MACHINE.

Application filed May 18, 1921. Serial No. 470,513.

To all whom it may concern:

Be it known that I, WILLIAM A. LORENZ, a citizen of the United States, residing in Hartford, in the county of Hartford and State of Connecticut, have invented certain new and useful Improvements in Paper-Crinkling Machines, of which the following is a specification.

This invention relates to crinkling or crêping either plain or corrugated paper or paper stock.

According to the usual practice, a web of moistened paper is led over a cylinder, to which it is caused to adhere by reason of its moist condition. The cylinder usually drives the paper against a doctor-blade, which performs two functions, namely, it crinkles the paper transversely and simultaneously strips it from the cylinder. The paper usually adheres tightly to the cylinder, in order to enable the latter to crush it with sufficient force against the doctor-blade, and also to prevent the doctor-blade from stripping the paper from the cylinder prematurely, that is, before the paper advances to the crushing point.

Premature stripping of the paper is found to be a serious objection, especially where heavy paper is used, because, if the paper is partly or wholly stripped from the cylinder before it reaches the doctor-blade, the crushing or crinkling operation is weakened, since the strip of paper is not driven with the required force against the doctor-blade or abutment. Moreover, it is objectionable to moisten the paper so thoroughly as usually required, inasmuch as it is expensive to dry it, and the drying ovens occupy considerable room, while the product is apt to be of an inferior quality when the paper is heavily moistened.

One of the objects of the invention is to overcome these difficulties, and the object is attained by substituting for the doctor-blade an apparatus which forms a constricted throat into which the paper advances, the throat being choked by the paper, thus obstructing the progress of the paper freshly entering the throat, whereby the advancing paper becomes transversely crinkled or crêped in forcing a passage through the throat. One element forming the throat is preferably a roll, which is preferably power-driven, being geared to the

main cylinder; while the other element 55 forming the throat is preferably a plate which curves around said roll for some distance, forming the required narrow crevice or throat. One edge of said plate may be in contact with the cylinder, and it may be 60 sharpened and strip the paper from the cylinder, and guide it into the throat, preparatory to becoming crinkled therein. The delivery end of the throat is more constricted than the intake end thereof, said constriction 65 being of service in retarding and hence effecting the crinkling of the paper.

In carrying out the invention in another form, the main cylinder may be peripherally grooved, and the paper or paper stock may 70 be longitudinally corrugated by the co-operation of said cylinder with a companion grooved roll. The fluted throat into which the paper is delivered by the cylinder comprises a grooved roll and a throat plate 75 which is also grooved, so that the paper may enter the throat in a corrugated condition, and, after being therein crinkled, emerges in a longitudinally corrugated and transversely crinkled condition. 80

Other features and advantages will hereinafter appear.

In the accompanying drawings,

Figure 1 is a plan, and Figure 2 is a sectional side elevation of one form of crinkling 85 machine for carrying out the present improvements.

Figure 3 is an enlarged sectional elevation of the parts composing the crinkling throat seen at Figure 2. 90

Figure 4 is a plan, and Figure 5 is an elevation, of a machine for both corrugating and crinkling paper according to the present improvements.

Figure 6 is an enlarged sectional elevation, showing details of the throat and the improving means for adjusting the extent of the opening at the constricted delivery end of the throat. 95

The web of paper is shown in the form 100 of a roll 10. The unfinished product of a paper-making machine may be used in carrying out the present improvements in either form. The rotation of the roll 10 is retarded by a weighted strap 11. The web 105 is led over a guide-roll 12 and onto a main cylinder 13, and passes down around the same into a tank 14 containing water 15,

whereby the web may be moistened. As the paper emerges from the tank, it is pressed by a regulatable soft rubber roll 16 against the cylinder 13, thereby squeezing out surplus water and also causing the moistened web to adhere to the surface of the cylinder with sufficient tightness to be of service in crushing the paper to form transverse wrinkles therein.

10 The paper is stripped from the cylinder by means of the sharpened edge 17 of a plate 18, and is conducted up between said plate and a roll 19. The latter preferably runs upon the cylinder, and is power-driven by 15 means of a pinion 20 upon shaft 21 of the roll, said pinion meshing with a gear 22 on shaft 23 of the main cylinder 13. The roll 19 therefore may revolve at the same surface speed as the main cylinder 13, and is of 20 service in aiding to force the paper through the throat after it is stripped from said cylinder. Said plate 18 curves around the roll, 19 preferably for about a quarter of its circumference, and forms therewith a constricted throat to constitute a crinkling passage for the paper. The curvature of the plate or segment 18 is nearly concentric with the roll, and is preferably closer to the roll at the delivery end of the throat. Such constriction may be relied upon to cause the 30 paper to choke in the throat, whereby the paper advancing from the main cylinder 13 is crushed or formed into wrinkles, beginning preferably at about a point 24, Figure 35 3, a short distance from the cylinder. The crinkled paper slowly emerges from the throat, and is carried off by a delivery belt 25.

40 In starting the machine, the leading edge of the web may be crinkled up by hand and introduced into the throat, through which it cannot readily pass because of its crinkled condition, and therefore the throat becomes choked at its delivery end, and the oncoming 45 paper itself also becomes crinkled in forcing the leading end of the web out of the constricted end of the throat. The portion of the web thus crinkled becomes in turn an obstruction in the delivery end of the throat, thus causing fresh oncoming portions to become crinkled, and so on.

50 The plate and roll may be so close as to secure efficient crinkling, but if a still narrower crevice is desired at the delivery end 55 of the throat, there may be employed a plate or gate 26 to partly close said end, the same having a rounded lower edge 27 to avoid tearing the paper while obstructing its progress. This gate may be secured by bolts 28 upon a flange 29 extending up from a bar 30, to which the stripper plate 18 is secured by screws 31.

Upon the ends of the plate 18 may be cast or provided arms 32, these arms being pivoted upon the axle 21 of the roll, so as to

permit swinging adjustment of the throat plate 18; and a spring 33 may be used for pressing the lower or stripping edge of the plate 18 against the cylinder 13, to render it efficient in stripping the paper from the cylinder.

Referring more particularly to Figures 4, 5, and 6, the web may be longitudinally corrugated as well as transversely crinkled. The main cylinder 34 may be peripherally 75 grooved at 35, and two grooved rolls 36, 37, may press the paper into the grooves of the cylinder 34, to corrugate the paper. The original web 38 may be damped, or the dry paper may be moistened by means of a 80 sprinkler-pipe 39, Figure 5, as well as by the water in the tank 14. The crinkling roll 40 is peripherally grooved at 41 to match the grooves 35 in the cylinder 34; and the curved stationary throat-plate that co-operates with 85 roll 40 may be correspondingly grooved as at 42 on its concave side, the curved plate and roll taken together form a wavy or fluted passage or throat for the corrugated paper. This passage is narrower or obstructed at or towards its delivery end, so that the corrugated paper forced through 90 said passage becomes crinkled transversely because of such narrowing, the corrugated and crinkled product being seen at 43. The 95 grooved curved throat-plate is designated as 44 and may be provided with ears 45 whereby it is fixedly supported on opposite brackets 46 provided upon the framework of the machine. The remainder of the curved plate is designated as 47, and is hinged at 48 to the main plate 44, so that an adjustment may be made at the delivery end of the 100 throat to open or narrow the same. This 105 adjustment may be effected by one or more screws 49, having bearings in a fixed plate at 50 and threaded at 51 into the hinged plate near the delivery end thereof. By turning the screw, this hinged plate may be rocked up and down, and its position relative to the roll 40 may be minutely adjusted 110 so as to secure the desired degree of crinkling of the paper.

Variations may be resorted to within the scope of the invention, and portions of the improvements may be used without others.

Having thus described my invention, I claim:

1. The combination with power-driven paper-advancing means, of co-operative devices forming a throat into which the paper is advanced, one of said co-operative devices being a roll and the other being a stationary plate, and said throat constricted to cause the paper advancing thereinto to become crinkled in forcing a passage, said advancing means in the form of a cylinder, and said plate having a stripping edge to contact with the cylinder, means to moisten the paper, and means in advance of said throat 125 130

to press the surplus moisture out of the paper and cause it to adhere to the cylinder.

2. The combination with power-driven paper-advancing means, of co-operative devices forming a throat into which the paper is advanced, one of said co-operative devices being a roll and the other being a stationary plate, said plate being of segmental form and curving around said roll close thereto 10 to form a narrow crevice or throat between the plate and the roll to cause the paper advancing thereto to become crinkled in forcing a passage, said advancing means in the form of a cylinder, and said plate having a stripping edge to contact with the cylinder, said roll connected to said cylinder to rotate at the same surface speed, one edge of said curved plate in contact with the cylinder, to serve to strip the paper from 15 the cylinder and guide it into the throat.
3. The combination with power-driven paper-advancing means, of co-operative devices forming a throat into which the paper is advanced, one of said co-operative devices 20 being a roll and the other being a stationary plate, means being provided at the delivery end of the throat to restrict the passage for the paper to cause the paper advancing thereto to become crinkled in forcing a 25 passage.

4. The combination with a main cylinder and means for moistening a web, of a roll to press surplus moisture from the web and cause the web to adhere to the cylinder, a 30 plate having a sharpened edge to strip the paper from the cylinder, and a roll geared to said cylinder to run thereon, said plate extending around said roll to form therewith a throat to receive the paper stripped 35 from said cylinder, said throat constricted to obstruct the passage of the paper through the throat, whereby the incoming paper is transversely crinkled against the obstruction.

- 45 5. The combination with a main cylinder and means for moistening a web, of a roll to press surplus moisture from the web and cause the web to adhere to the cylinder, a plate having a sharpened edge to strip the 50 paper from the cylinder, and a roll geared to said cylinder to run thereon, said plate extending around said roll to form therewith a throat to receive the paper stripped from said cylinder, said throat constricted to 55 obstruct the passage of the paper through the throat, whereby the incoming paper is transversely crinkled against the obstruction, said plate being in the form of a segment which is nearly concentric with said roll and approaches nearest to the roll at the delivery 60 end of the throat.

- 65 6. The combination with power-driven paper-advancing means, of co-operative devices forming a throat into which the paper is advanced, one of said co-operative devices

being a roll and the other being a stationary plate, and said throat constricted to cause the paper advancing thereto to become crinkled in forcing a passage, and a delivery belt at the delivery end of the throat.

7. The process of crinkling paper, consisting in moistening the paper, pressing the moist paper against a carrier, stripping the paper from the carrier, and thrusting it into a throat, one side whereof tends to advance the paper and the other side whereof tends to hold back the paper, causing the paper to choke the throat and crinkle itself in forcing a passage.

8. The combination with power-driven paper-advancing means, of co-operative devices forming a throat into which the paper is advanced, one of said co-operative devices being a roll and the other being a stationary plate, a plate or gate being employed for partially closing the delivery end of the throat, to cause the paper advancing thereto to become crinkled in forcing a passage.

9. The combination with power-driven paper-advancing means, of co-operative devices forming a throat into which the paper is advanced, one of said co-operative devices being a roll and the other being a stationary plate, a plate or gate being employed for partially closing the delivery end of the throat, to cause the paper advancing thereto to become crinkled in forcing a passage, said gate having a rounded edge to avoid tearing the paper while obstructing its progress.

10. The combination with power-driven paper-advancing means, of co-operative devices forming a throat into which the paper is advanced, one of said co-operative devices being a roll and the other being a stationary plate, said plate being of segmental form and curving around said roll close thereto to form a narrow crevice or throat between the plate and the roll to cause the paper advancing thereto to become crinkled in forcing a passage, said advancing means in the form of a cylinder, and said plate having a stripping edge to contact with the cylinder, said roll connected to said cylinder to rotate at the same surface speed, and arms upon which said plate is carried, said arms pivoted about concentrically of said roll to permit a swinging adjustment of said plate.

11. The combination with power-driven paper-advancing means, of co-operative devices forming a throat into which the paper is advanced, one of said co-operative devices being a roll and the other being a stationary plate, said plate being of segmental form and curving around said roll close thereto to form a narrow crevice or throat between the plate and the roll to cause the paper advancing thereto to become crinkled in forcing a passage, said advancing means in the form of a cylinder, and said plate hav-

- ing a stripping edge to contact with the cylinder, said roll connected to said cylinder to rotate at the same surface speed, arms upon which said plate is carried, said arms pivoted about concentrically of said roll to permit a swinging adjustment of said plate, and means for pressing the stripping edge of said plate against the cylinder.
12. The combination with power-driven paper-advancing means, of co-operative devices forming a throat into which the paper is advanced, one of said co-operative devices being a roll and the other being a stationary plate, said plate being of segmental form and curving around said roll close thereto to form a narrow crevice or throat between the plate and the roll to cause the paper advancing thereinto to become crinkled in forcing a passage, said advancing means in the form of a cylinder, said plate having a stripping edge to contact with the cylinder, said roll connected to said cylinder to rotate at the same surface speed, arms upon which said plate is carried, said arms pivoted about concentrically of said roll to permit a swinging adjustment of said plate, means for pressing the stripping edge of said plate against the cylinder, and a crinkling plate or gate placed at the delivery portion of the throat.
13. The combination with power-driven paper-advancing means, of co-operative devices forming a throat into which the paper is advanced, one of said co-operative devices being a roll and the other being a stationary plate, said plate being of segmental form and curving around said roll close thereto to form a narrow crevice or throat between the plate and the roll to cause the paper advancing thereinto to become crinkled in forcing a passage, said advancing means in the form of a cylinder, said plate having a stripping edge to contact with the cylinder, said roll connected to said cylinder to rotate at the same surface speed, said curved plate provided with an adjustment for varying the capacity of the throat at its delivery end.
14. The combination with power-driven paper-advancing means, of co-operative devices forming a throat into which the paper is advanced, one of said co-operative devices being a roll and the other being a stationary plate, said plate being of segmental form and curving around said roll close thereto to form a narrow crevice or throat between the plate and the roll to cause the paper advancing thereinto to become crinkled in forcing a passage, said advancing means in the form of a cylinder, said plate having a stripping edge to contact with the cylinder, said roll connected to said cylinder to rotate at the same surface speed, said plate forming two portions, one hinged to the other, the stripper portion of said plate being sta-
- tionary and the delivery portion of said plate being adjustable for varying the capacity of the throat, thereby to regulate the crinkling.
15. In combination, a crinkling device 70 comprising a curved plate and a power-driven roll for carrying the paper along said curved plate, said plate being placed so closely to said roll that the paper is pressed or obstructed between the plate and the roll 75 and thereby cross-crinkled, and means for wetting the paper to prepare it for being crinkled by said device.
16. The combination with a power-driven cylinder and means to cause the paper to cling to the cylinder, of a curved plate forming a stripper to strip the paper from the cylinder, a spring to press said plate against the cylinder, and means co-operating with said plate to form a throat by which the 80 paper is transversely crinkled.
17. The combination with a power-driven cylinder, of co-operative members forming a throat into which the paper is thrust by the cylinder, one of said members being stationary, and means for closing the aperture at the delivery end of the throat in order to hold back the paper for the purpose of causing the same to crinkle itself. 85
18. The combination with power-driven paper-advancing means, of co-operative devices forming a fluted throat into which paper is advanced, one of said co-operative devices being a grooved roll and the other being a stationary grooved plate, and said throat constricted to cause the paper advancing thereinto to become crinkled in forcing its passage through the throat. 90
19. The combination with power-driven paper-advancing means, of co-operative devices forming a fluted throat into which paper is advanced, one of said co-operative devices being a grooved roll and the other being a stationary grooved plate, said throat constricted to cause the paper advancing thereinto to become crinkled in forcing its passage through the throat, said advancing means in the form of a peripherally grooved cylinder, and said plate having a serrated stripping edge to contact with the grooves 100 and ridges of the cylinder. 105
20. The combination with power-driven paper-advancing means, of co-operative devices forming a fluted throat into which paper is advanced, one of said co-operative devices being a grooved roll and the other being a stationary grooved plate, said throat constricted to cause the paper advancing thereinto to become crinkled in forcing its passage through the throat, said advancing means in the form of a peripherally grooved cylinder, said plate having a serrated stripping edge to contact with the grooves and ridges of the cylinder, means to moisten 110 the paper, and means in advance of said 115
- 120
- 125
- 130

throat to press the surplus moisture out of the paper and press it into the grooves and cause it to adhere to the cylinder.

21. The combination with power-driven paper-advancing means, of co-operative devices forming a fluted throat into which paper is advanced, one of said co-operative devices being a grooved roll and the other being a stationary grooved plate, said throat 10 constricted to cause the paper advancing thereinto to become crinkled in forcing its passage through the throat, said advancing means in the form of a peripherally grooved cylinder, and said plate having a serrated stripping edge to contact with the grooves and ridges of the cylinder, said plate of segmental form and curving around said roll to form a narrow crevice or throat between the plate and the roll.
- 20 22. The combination with power-driven paper-advancing means, of co-operative devices forming a fluted throat into which paper is advanced, one of said co-operative devices being a grooved roll and the other 25 being a stationary grooved plate, said throat constricted to cause the paper advancing thereinto to become crinkled in forcing its passage through the throat, said advancing means in the form of a peripherally grooved 30 cylinder, and said plate having a serrated stripping edge to contact with the grooves and ridges of the cylinder, said plate of segmental form and curving around said roll to form a narrow crevice or throat between the 35 plate and the roll, means being provided for varying the constriction of the throat.

23. The combination with a grooved main cylinder and means for moistening a web, of a grooved roll to force the web into the 40 grooves of the cylinder and press surplus moisture from the web and to cause the web to adhere to the cylinder, a grooved plate having a sharpened serrated edge to enter the grooves of the cylinder and strip the paper from the cylinder, and a grooved roll 45 geared to said cylinder, said grooved plate extending around said roll to form there-with a fluted throat to receive the paper stripped from said cylinder, said throat having a constriction to obstruct the passage of the paper, whereby the incoming 50 paper is transversely crinkled.

24. The process of crinkling a paper web, consisting in moistening the web, pressing the moist paper against a grooved carrier, to 55 corrugate the web, stripping the web from the carrier, and conducting it into a grooved or fluted throat, one side whereof tends to advance the web and the other side whereof tends to hold back the web, causing the paper to choke the throat and crinkle itself in forcing a passage.

25. The combination with a grooved main cylinder and means for moistening a web, 60 of a grooved roll to force the web into the

grooves of the cylinder and press surplus moisture from the web and to cause the web to adhere to the cylinder, a grooved plate having a sharpened serrated edge to enter the grooves of the cylinder and strip the 70 paper from the cylinder, and a grooved roll geared to said cylinder, said grooved plate extending around said roll to form there-with a fluted throat to receive the paper stripped from said cylinder, said throat 75 having a constriction to obstruct the passage of the paper, whereby the incoming paper is transversely crinkled, said plate provided with an adjustment for varying the capacity of the throat at its delivery end. 80

26. The combination with a grooved main cylinder and means for moistening a web, of a grooved roll to force the web into the grooves of the cylinder and press surplus moisture from the web and to cause the web 85 to adhere to the cylinder, a grooved plate having a sharpened serrated edge to enter the grooves of the cylinder and strip the paper from the cylinder, and a grooved roll 90 geared to said cylinder, said grooved plate extending around said roll to form there-with a fluted throat to receive the paper stripped from said cylinder, said throat having a constriction to obstruct the passage of the paper, whereby the incoming 95 paper is transversely crinkled, said plate forming two portions, one hinged to the other, the stripper portion of said plate being stationary and the delivery portion of said plate being adjustable for varying 100 the capacity of the throat, thereby to regulate the crinkling.

27. In combination, a crinkling device comprising a curved grooved plate and a power-driven grooved roll for carrying the 105 paper along said curved plate, said plate being placed so closely to said roll that the paper is obstructed between the plate and the roll and thereby cross-crinkled.

28. In combination, a crinkling device 110 comprising a curved grooved plate and a power-driven grooved roll for carrying the paper along said curved plate, said plate being placed so closely to said roll that the paper is obstructed between the plate and the roll and thereby cross-crinkled, and 115 means for wetting the paper to prepare it for being crinkled by said device.

29. The combination with a power-driven grooved cylinder and grooved means to cause the paper to cling to the cylinder, of a curved grooved plate having a serrated edge forming a stripper to strip the paper from the cylinder, a spring to press said plate against the cylinder, and grooved 120 means co-operating with said plate to form a throat by which the paper is transversely crinkled. 125

30. The combination with a power-driven grooved cylinder, of co-operative grooved 130

matched members forming a fluted throat into which the paper is thrust by the cylinder, one of said members being stationary, and said throat being of such small capacity that the paper is crinkled in forcing a passage.

31. The combination with a power-driven grooved cylinder, of co-operative grooved matched members forming a fluted throat into which the paper is thrust by the cylinder, one of said members being stationary,

and said throat being of such small capacity that the paper is crinkled in forcing a passage, one of said members being in the form of a stripper having a serrated edge to separate the paper from the cylinder and guide it into the throat. 15
